UNITED STATES PATENT OFFICE.

WILLIAM HURD HILLYER, OF ATLANTA, GEORGIA.

ELECTRICALLY-CONTROLLED SWITCH.

SPECIFICATION forming part of Letters Patent No. 760,988, dated May 24, 1904.

Application filed January 21, 1903. Serial No. 139,987. (No model.)

To all whom it may concern:

Be it known that I, WILLIAM HURD HILLYER, a citizen of the United States, residing at Atlanta, in the county of Fulton and State 5 of Georgia, have invented new and useful Improvements in Electrically - Controlled Switches, of which the following is a specification.

My invention relates to new and useful improvements in electrically-operated switches; and its object is to provide a simple and inexpensive device which may be readily installed in ordinary electric-railway systems and by means of which the switch will be automatically shifted as a car approaches the same.

A further object is to provide means upon the car whereby the motorman or any other person thereon may so direct the current of electricity as to shift the switch in the desired 20 direction.

A further object is to provide novel means for conducting the current from the trolley to the cut-off arranged upon the car.

With the above and other objects in view 25 the invention consists in the novel construction and combination of parts hereinafter more fully described and claimed, and illustrated in the accompanying drawings, and in which—

Figure 1 is a diagrammatical view showing the relation of a trolley and the contacts therefor with the switch and also showing the circuits connecting the same. Fig. 2 is an enlarged transverse section through the contacts and showing a trolley in position therebetween. Fig. 3 is a side elevation of a trolley arranged to be used in connection with my improved switch-operating mechanism, the base of said trolley being shown in section. Fig. 4 is an enlarged view showing in section my improved contact device for conducting a current from the trolley to the top of the car. Fig. 5 is a plan view of the switch and showing the relation of the solenoids to the tongue thereof. Fig. 6 is an enlarged section on line 45 *x x*, Fig. 5. Fig. 7 is a detail view of the switch-tongue, and Fig. 8 is a plan view of the conductor-ring.

Referring to the figures by numerals of reference, 1 is a switch-tongue having a depending lug 2, which is adapted to fit within an

aperture 3, formed within an armature 4 at a point between the ends thereof. This armature extends laterally from opposite sides of the switch-tongue and is slidably mounted within solenoids 5, which are arranged at opposite sides of the switch and are preferably fitted within boxes 6 and secured in any suitable manner thereto. As the armature is slidably mounted within the solenoids, it is obvious that it will be drawn into one or the other accordingly as they are energized.

The trolley-wire 7, arranged above the track upon which the switch is located, is provided at a point in advance of the switch with sleeves 8, formed of copper or other conducting material, and washers 9 of suitable insulating material are clamped between these sleeves at suitable intervals and receive bolts 10, which also pass through insulators 11, arranged at opposite sides of the sleeves and adapted to 65 abut against the inner surfaces of contact-plates 12 and 13. These plates are formed of conducting material and are securely held in position against the outer ends of the insulators 11 by means of the securing-bolts 10, before referred to. Two sets of contact-plates, as above described, are arranged upon the trolley-wire 7, and one is located in advance of the other. A wire 14 connects the plate 13 of one of the sets of contacts with one of 70 the solenoids 5, while a wire 15 connects the plate 12 of the other set of contacts with the remaining solenoid.

In order to operate the switch having contacts, as above described, connected with the operating solenoids, it is necessary to provide a trolley 16 with a contact 17 at one side thereof, which is adapted when the trolley is brought into position upon one of the sleeves 8 to contact with the plate 13 adjacent thereto. 85 The current will thus be directed from the trolley-wire 7 to the trolley 16 and through contacts 17 and 13 to wire 14 and the solenoid connected therewith, and as soon as said solenoid is energized the armature 4 will be 90 drawn thereinto and swing tongue 1 upon its fulcrum. A ring 18 is clamped upon the pole of the trolley and is insulated therefrom, and the ends of this ring form a contact 19, which is adapted when the trolley is brought into 95 100

position upon one of the sleeves 8 to bear upon the adjacent contact-plate. The neck 20 of the trolley-swivel 21 is secured to the disk 22, formed of wood, vulcanite, or other insulating material, and preferably encircled by a band 23, which protects the same from injury. A plate 24 is secured to the under surface of disk 22, and a tube 25, of rubber or other insulating material, projects through said plate 24 and the disk 22 and extends upward to a point upon the trolley-pole a suitable distance from the swivel 21. This tube contains a wire 26, which extends from and is electrically connected with the contact 19, and the lower end 15 of said wire is soldered or otherwise secured to a plug 27, which extends from the lower end of tube 25 and is provided at its outer end with a contact-button 28. A bow-spring 29 incloses the plug at a point above the button, 20 and the ends thereof bear upon the plate 24. A ring 30 is preferably arranged upon the lower end of tube 25 and serves to clamp said tube upon the plug 27, and thereby retain the plug in position therein. Spring 29 is adapted 25 to hold the button 28 at all times in contact with a ring 31, arranged upon the top 32 of the car upon which the trolley is mounted, and said ring is concentric with the swivel-neck of the trolley. This ring is formed of 30 conducting material and is connected, by means of a wire 32, with a switch 33, located upon the car at a point within convenient reach of the motorman. This switch is also connected, by means of a wire 34, to the motor of the car, 35 which is electrically connected with the trolley-pole by a wire 36 in the usual manner. The ring 31 may be provided with a groove 35 in one face thereof for the reception of the wire 32.

40 When a car approaches the switch and it is desired to go to the left, the switch 33 is shifted to the left by the motorman at any time prior to the arrival of the car at a point below the contact-plates 12 and 13. When the trolley reaches these contacts, it will pass between the first set, and contact 17 will be promptly brought against plate 13 and the circuit established from the trolley to wire 14 and its solenoid, as before described, and the switch-tongue will be swung to the left. As the switch 33 when moved to the left by the motorman closes the circuit between the wires 26 and 34, it is obvious that as soon as the trolley passes between the second set of contacts 12 and 13 45 the contact 19 will bear upon plate 12 and a circuit will be promptly established from the trolley-pole through wire 36, the motor, wires 34 and 26, the contacts 19 and 12, and wire 15, and the solenoid connected to said wire will 50 be energized and draw the armature toward it, thereby shifting the tongue 1 to the right and opening the track to the left. As the two sets of contacts 12 and 13 are removed from each other, it will be understood that the two 55 solenoids will not be energized at the same

time. When it is desired to travel to the right of the switch, the closer 33 is shifted to the right, and when contact 17 of the trolley is brought against the contact-plate 13 tongue 1 will be shifted to the left by the energized solenoid connected to wire 14, and when the trolley passes between the second set of contact-plates 12 and 13 the other solenoid will be unaffected in view of the fact that the contact 19 has been thrown out of circuit with wire 75 34 by the circuit-closer 33.

It will of course be understood that a ground-wire 37 extends from each of the solenoids 5 to complete the circuit with the trolley-wire 7.

It will be seen that this device is extremely 80 simple and can be readily used in connection with the trolley systems now in use, and by means thereof the motorman, conductor, or other authorized person upon a car may readily 85 swing the tongue of the switch in any desired direction without stopping or leaving the car.

In the foregoing description I have shown the preferred form of my invention; but I do not limit myself thereto, as I am aware that 90 modifications may be made therein without departing from the spirit or sacrificing any of the advantages thereof, and I therefore reserve the right to make such changes as fairly fall within the scope of my invention.

Having thus described the invention, what 95 is claimed as new is—

1. In an electrically-operated switch, the combination with a switch-tongue, an armature connected therewith, and oppositely-disposed solenoids adapted to receive the armatures; of contact-plates arranged at opposite sides of the trolley-wire, electrical connections between said contact-plates and their respective solenoids, a trolley adapted to conduct a current from the trolley-wire to one of said contacts, and means whereby the current may be conducted through the trolley and a motor connected therewith to the other contact. 105

2. In an electrically-operated switch, the combination with a tongue, an armature connected therewith, and solenoids arranged at opposite sides of the tongue and adapted to receive the armature; of contacts at opposite sides of a trolley-wire and electrically connected to their respective solenoids, a trolley 110 for conducting a current from said wire to either of the contacts, said trolley having a contact at one side thereof and electrically connected therewith, a contact extending from the opposite side and insulated therefrom, a disk secured to the trolley and revoluble therewith, a stationary ring below the disk, a movable electrical connection between said insulated contact and the ring, and means whereby the current may be conducted from the 115 trolley to a motor and the ring, the two contacts on the trolley being adapted to bear upon the respective contact-plates. 120

3. In a switch of the character described, a circuit-closing trolley having a contact extend- 125

ing from one side thereof and integral therewith, a contact extending from the opposite side and insulated therefrom, a disk secured to the trolley and revoluble therewith, a stationary contact-ring below said disk, a button 5 slidably mounted thereon and depending from the disk, means for holding the button normally in contact with the ring, and an electrical connection between said button and the insulated contact.

4. In a switch of the character described, a circuit-closing trolley having a contact extending from one side thereof and integral therewith, a ring secured to the trolley and insulated therefrom, a contact extending from the 15

ring, a disk secured to and revoluble with the trolley, a stationary contact-ring below the disk, a tube extending through the disk from the trolley, a plug therein, a button upon the plug slidably mounted on the contact-ring, a spring for holding the button normally in contact with the ring, and a wire within the tube connecting the plug with the insulated contact.

In testimony whereof I affix my signature in presence of two witnesses.

WILLIAM HURD HILLYER.
